UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK.

SIGNAL SYSTEM.

Original application filed May 16, 1924, Serial No. 713,694, Patent No. 1,664,860, dated April 3, 1928.
Divided and this application filed February 28, 1928. Serial No. 257,614.

This invention relates broadly to signaling, and more particularly to a terminal circuit of a multiplex two-way transmission and receiving system for radio communication, the 5 application being a division of application Serial No. 713,694, filed May 16, 1924, Patent No. 1,664,860, patented April 3, 1928.

The objects of the invention are to provide for the operation of several simultaneous two- 10 way communications over a radio link, using a single antenna or other radiating structure at each terminal station, and to do this with a minimum of interference between the two-way channels employed for such communications and between the transmitting and receiving portions of each two-way channel.

In a specific embodiment of the invention the several two-way terminal circuits are connected to individual branches of an antenna 20 having a common aerial portion, such aerial portion and each branch being together separately resonant at the frequencies of both the transmitted and the received waves corresponding to the two-way channel connected to 25 that branch. Each branch also includes anti-resonant circuits equal in number to the remaining two-way channels, for preventing interference therefrom. The anti-resonant circuits, therefore, make each branch, which 30 is individual to a two-way channel in combination with the aerial portion, functionally independent of each of the other similar combinations of individual branch and common aerial portions.

35 Anti-resonant means may also be included in the receiving portion of each two-way channel associated with an antenna branch for preventing interference between the transmitting and receiving portions of each 40 such channel. Alternatively, the relation between the transmitting and receiving portions of each channel may be such as to make possible the utilization of the transmitting frequency to combine with the incoming signal 45 wave and thereby step down its frequency, as in well known types of plural detection receiving systems.

The invention will be more clearly understood by reference to the following specification and the accompanying drawings in 50 which the single figure shows a circuit arrangement for a plurality of two-way multi-

plex channels operating in connection with the same antenna.

Referring to the drawing, three channels 55 have been shown at 1, 2 and 3. Each channel includes circuits for screening it against interference from adjacent channels, while permitting transmission and reception of energy in the particular channel in which the screening means may be located.

60 Channel 1 is divided into a transmitting circuit 4 and a receiving circuit 5. The transmission system connected to the transmission circuit 3 may include a source of sustained oscillations designated 6 connected to impress 65 energy of constant frequency upon a modulation circuit including electron tube 7.

The high frequency oscillations from the 70 source 6 may be modulated at voice frequency from a circuit represented at 8 and the modulated high frequency oscillations are impressed upon the amplification system 9. This system operates to increase the amplitude of the energy to be transmitted and to 75 deliver the amplified energy to the radiating antenna system, comprising antenna 10, inductance 11, capacity 12 and ground 13.

Circuits consisting of inductance 14 shunted by capacity 15, and inductance 16 shunted by capacity 17 are provided in the antenna 80 connection for the purpose of screening the communication channel from reaction or disturbance of oscillations produced in adjacent channels as will be hereinafter described.

85 The receiving system of channel 1 includes a circuit consisting of inductance 18 and shunt capacity 19 which is closely resonant to the frequency of the source 6 of the transmitting circuit 4, but can be detuned from that frequency sufficiently to permit a desired amount of energy from the local transmitting channel to flow in the receiving circuit. This energy is used in cooperation with the incoming signal energy for the production of a beat note, 90 enabling the signals to be observed.

95 The receiving circuit 5 includes the primary antenna inductance 20 and tuning condenser 21 connected to ground 22. The frequency derived from the inter-action of 100 the incoming signal energy with the energy from the local transmitting source may be combined in the detector tube 23 to produce a beat frequency wave and the beat frequency

wave is impressed upon a detector circuit including tube 24 which operates to reproduce the signal transmitted from the distant station.

5 The second duplex channel represented by connection 2 with the antenna 10 has circuits interposed between the transmitting and receiving apparatus and the antenna system designed to eliminate the passage of undesired 10 disturbances or reactions from the associated channels into the transmitting or receiving apparatus of the channel 2. These circuits include inductances 25 and 26 shunted by condensers 27 and 28, respectively.

15 The transmitter for this channel is represented as having a source of sustained oscillations 29 connected with suitable modulation and amplification circuits represented generally at 30. The oscillations to be transmitted 20 are modulated at voice frequencies through circuit 31. The transmitting energy is delivered to the antenna system through inductance 32 connected in the antenna and ground circuit in series with condenser 33.

25 In the lead from the antenna 10 through connection 2 to the receiving apparatus in this channel there is interposed a circuit including an inductance 34 shunted by condenser 35 to constitute a circuit tuned to exclude oscillations supplied by the local source 29 to the associated transmitter circuit.

The receiver energy is impressed upon the receiving circuit through primary inductance 36 shunted by tuning condenser 37. A local 35 source of oscillations may be supplied by means of a local generator 38 coupled with the secondary winding 39 through an inductance 40.

An electron tube 41 is connected to function 40 as a detector which operates to reduce the frequency of the incoming signal wave to an intermediate frequency determined by the frequency of the source 38. The intermediate frequency wave is amplified by amplifier 42 and selectively impressed upon another detector 43 through a series of selective circuits or filter 44. The signal produced by the detector 43 is applied to responsive device 45. The frequency of source 38 is fixed with respect to the incoming wave to produce a wave 50 of intermediate frequency which should be different from that produced by combining the incoming signal wave with the transmitted wave for this channel. The intermediate 55 frequency wave should preferably have a frequency different from that produced by combining the incoming signal wave with any of the waves used in the other channels.

60 Channel 3 is connected with the antenna 10 through a lead having circuits interposed therein for excluding wave frequencies used in the associated channels. The circuits for doing this comprise inductances 46 and 47 shunted by condensers 48 and 49 respectively.

65 The transmitting circuit 50 of channel 3

may be provided with a local carrier source of oscillations designated as having a frequency F , the energy from which is modulated by a signal in the manner described with reference to transmitting channels 1 and 70 2. The signal modulated wave is impressed on the antenna circuit through the inductive coupling 51.

The receiving system for the channel 3 includes a circuit in series therewith comprising 75 inductance 52 and condenser 53 which functions to exclude from the receiving system the oscillations supplied to the transmitting circuit. It may function as in channel 1 to permit a desired amount of the locally transmitted energy to flow to the receiving circuit. The receiver may be coupled to the system by the winding 54 inductively associated with the winding 55. Condensers 56 and 57 are used to assist in tuning the coupled circuits to 80 85 the desired frequency.

It will be observed that means are provided in each of the several channels for suppressing reactions and interference from currents occurring simultaneously in the other channels. In channel 1, circuits 14, 15 and 16, 17 90 will suppress undesired oscillations or currents which might be impressed upon channel 1 by reason of the flow of energy proper to channels 2 or 3.

The circuit 18, 19, in the receiving portion of channel 1, excludes from the receiving circuit all energy except a desired amount, derived from the outgoing carrier wave supplied by the oscillator 6 for outgoing transmission over channel 1, which may be utilized in reception.

In channel 2, the circuits 25, 27 and 26, 28 exclude undesired currents which may be supplied from channel 1 or 3. The circuit 34, 105 35 in channel 2 prevents too great reaction of the sustained wave supplied for transmission by generator 29, upon the receiving portion of the channel.

In channel 3 the circuits 46, 48 and 47, 49 110 exclude undesired currents which may be supplied from channels 1 and 2, while the circuit 52, 53, in the receiving portion of the channel, operates to prevent undesired reaction of the sustained wave from circuit 50 in 115 such receiving portion of the channel.

All of the channels may, therefore, function in duplex operation in multiplex signaling on the same antenna 10 without mutual reaction or cross-talk.

120 The incoming signaling energy in the antenna system 10 distributes to the several receiving portions without interference since these receiving portions are respectively selective to their individual message waves.

125 For the purpose of clearly explaining the operation of the system, the transmitting frequency in duplex channel 1 may be assumed to have a value equal to f_1 . The incoming signaling energy in antenna 10 selected by chan-

nel 1 may have a frequency f_2 . A portion of the transmitting frequency f_1 being effectively utilized in the receiving portion of channel 1, as a local source of oscillations, 5 acts with the frequency f_2 in detector 23 from which is derived a beat note of a frequency $f_1 - f_2 = f_3$ which is detected in device 24 and observed.

In like manner channel 2 may have a local 10 source of transmitting energy of a frequency f_1^1 , and the incoming signaling energy in antenna 10 for this channel may be f_2^1 . If desired, the frequency f_1^1 may not be used as a local source in the receiving channel, but instead a local generator of a frequency f_4^1 may be employed. The beat frequency thus derived will be $f_4^1 - f_2^1 = f_3^1$ which may be detected in device 43 to enable the signals to be observed.

20 Similarly the channel 3 may have a transmitting wave of frequency f_1^{11} and the incoming frequency in antenna 10 for this channel may be f_2^{11} . A portion of the transmitting frequency f_1^{11} may be utilized as a local source, so that the beat frequency produced by the receiver will be

$$f_1^{11} - f_2^{11} = f_3^{11}.$$

The beat frequency f_3^{11} may be detected 30 and the signal indicated.

While the invention has been described in certain particular embodiments, it should be understood that modifications may be made and that the invention is not limited except 35 by the scope of the appended claims.

What is claimed is:

1. A multiplex radio communication system comprising in combination a single aerial antenna, a plurality of duplex units, each including a transmission channel and a receiving channel connected between said antenna and ground, each duplex unit employing different frequencies from all of the others, the receiving frequency of each duplex unit being different from the transmitting frequency of the same unit, means interposed between said antenna and each of said duplex units for preventing interference from currents occurring simultaneously in said other units, 45 and means comprising a loop tuned circuit interposed in the receiving portion of each of said units for preventing interference due to current flow in the transmitter channel.

2. A multiplex radio communication system comprising in combination a single antenna structure, a plurality of connections between said antenna structure and each of a plurality of duplex communication channels, each comprising transmitter and receiver 50 portions, each duplex unit employing different frequencies from all of the others, the receiving frequency of each duplex unit being different from the transmitting frequency of the same unit, means comprising a succession 60 of loop tuned circuits interposed in each of

said connections capable of passing currents of the frequencies used for transmitting and receiving by the respective duplex channels but preventing interference in each of said channels from currents existing simultaneously in said other channels, and separate means comprising a loop tuned circuit connected in each of said receiver portions for screening the receiver from undesired effects of the adjacent transmitter portion. 75

3. A multiplex radio communication system comprising, in combination, an antenna having a common aerial portion and a plurality of branches, a plurality of duplex channels, each comprising a transmitting 80 and a receiving portion, and each such channel connected in energy transfer relation to an individual one of said branches, and a plurality of means in each of said branches, each such means being selective at a frequency individual to the transmitting frequency of one of the other channels, for preventing interference from currents occurring simultaneously in said other channels, the transmitting and receiving apparatus of 85 each duplex channel employing frequencies sufficiently different to permit them to be separated by selective circuits, said frequencies being closer together in the frequency spectrum than any two frequencies used by 90 different duplex channels, whereby said plurality of means in each channel is capable of passing all of the frequencies used by the respective portions of the duplex channel in transmitting and receiving, while effectively 95 excluding currents of frequencies used by the other channels of the system. 100

4. A multiplex radio communication system, comprising in combination a single earthed antenna, a plurality of duplex units, 105 each including a transmission channel and a receiving channel connected between said antenna and the ground, each duplex unit employing different frequencies from all of the others, the receiving frequency of each 110 duplex unit being different from the transmitting frequency of the same unit, means interposed between said antenna and each of said duplex units for preventing interference caused by currents occurring simultaneously 115 in said other units, and means comprising a loop tuned circuit interposed in the receiver portion of each of said units for preventing interference caused by current flowing 120 in the transmitter portion.

5. A multiplex radio communication system, comprising in combination a single antenna structure, a plurality of connections between said antenna structure and each of a plurality of duplex communication channels, each comprising transmitter and receiver portions, each duplex unit employing different frequencies from all of the others, the receiving frequency of each duplex unit being different from the transmitting frequency 125 130

quency of the same unit, means comprising a succession of looped tuned circuits interposed in each of said connections capable of passing currents of the frequencies used for transmitting and receiving by the respective duplex channels but preventing interference in each of said channels due to currents existing simultaneously in said other channels, and separate means comprising a loop tuned circuit connected in each of said receiver portions for screening the receiver from undesired effects of the adjacent transmitter portion.

6. In a multiplex signaling system a two-way transmitting circuit, a plurality of two-way circuit branches connected thereto, frequency selective means included in each of said branches for selectively passing frequencies employed by the branch, while excluding frequencies employed by the other branches, a pair of oppositely directed one-way paths connected to each two-way branch and employing different frequencies for transmitting and receiving, a frequency selective means comprising a loop tuned circuit in each one-way receiving branch for

permitting the passage of waves employed for receiving while reducing to an unobjectionable amount the frequencies used by the transmitting path connected to the same two-way branch.

7. A multiplex system according to claim 6 in which a source of continuous waves is associated with the transmitting path connected to each two-way branch, said waves being separated in frequency from the frequency employed for receiving from the same two-way circuit branch by a super-audible frequency which is small compared with the frequency separation between two waves used by different similarly directed one-way branches, means in a receiving path for combining incoming waves with the waves from the said source in the transmitting path connected to the same two-way branch for producing a super-audible beat wave, and means in the receiving path for detecting said beat wave.

In witness whereof, I hereunto subscribe my name this 24th day of February, 1928.

RAYMOND A. HEISING.
